UNITED STATES PATENT OFFICE.

THOMAS W. RICKETTS, OF WHITEHALL, MICHIGAN.

DESIGN FOR A LAMP-STAND.

SPECIFICATION forming part of Design No. 22,550, dated June 20, 1893.

Application filed April 22, 1893. Serial No. 471,502. Term of patent 7 years.

To all whom it may concern:

Be it known that I, THOMAS W. RICKETTS, a citizen of the United States, residing at Whitehall, in the county of Muskegon and State of Michigan, have invented and produced a new and original Design for a Lamp-Stand; and I do hereby declare the following to be a full, clear, and exact description of the invention, such as will enable others skilled in the art to which it appertains to make and use the same.

This invention relates to a new design for a lamp stand.

The object is to produce a novel shape and configuration of a lamp-stand, having great beauty, and embellished with many artistically-arranged ornamental features.

The invention therefore consists in my design for a lamp stand, substantially as will be hereinafter described and claimed.

In the annexed drawings illustrating my invention: Figure 1 is a front elevation of my newly designed lamp-stand. Fig. 2 is a top plan view of the ornamental base thereof.

Like letters denote like parts in both figures.

There are two prominent features in my design one of which is a cornute or horn-shaped figure B, in a vertically-reversed position, its larger end being uppermost, while its curved lower and pointed end B' is projected downward toward the left. Mounted upon the top end of the horn-shaped figure B, is a semi-globular lamp shade D, supported by radial connections d d which touch the

horn shape B, while a cylindrical chimney form E, towers above the globular form D. 35 Alongside of the cornute figure B is the second prominent feature of my design which is an erect human figure C, martial in appearance and incased in armor, the arms of the figure grasping the enlarged upper end of the cornute figure B, and the head touching the latter, the whole combination indicating that the human figure C is supporting the horn in a vertical position, the lower pointed end B' of which lies in front of figure C and crosses 45 same as shown.

A denotes the base of the design for the stand of a lamp. On it stands the figure C. One foot of the figure rests centrally on the base A, while the other foot is slightly lifted 50 therefrom as if in the act of stepping. The base A has the ornamental lower projections a a and the entire surface of this base is highly inwrought with varied interlaced figuring which embellishes and beautifies its appearance.

What I claim is—

The design for a lamp stand, substantially as herein shown and described. In testimony whereof I affix my signature in 60 presence of two witnesses.

THOMAS W. RICKETTS.
